US00D956364S

(12) **United States Design Patent** (10) **Patent No.:** **US D956,364 S**
(45) **Date of Patent:** **** Jun. 28, 2022**

(54) **EARMUFF**

(71) Applicant: **NINGBO ALBERT NOVOSINO CO., LTD.**, Zhejiang (CN)

(72) Inventors: **Yonggui Zhang**, Zhejiang (CN); **Haibo Hu**, Zhejiang (CN)

(73) Assignee: **Ningbo Albert Novosino Co. Ltd.**, Ningbo (CN)

(**) Term: **15 Years**

(21) Appl. No.: **29/759,165**

(22) Filed: **Nov. 20, 2020**

(30) **Foreign Application Priority Data**

Oct. 17, 2020 (CN) 202030618608.7

Primary Examiner — Elizabeth J Oswecki

(57) **CLAIM**

The ornamental design for an earmuff, as shown and described.

DESCRIPTION

FIG. 1 is a perspective view of an earmuff showing our new design;

FIG. 2 is a front view thereof;

FIG. 3 is a back view thereof;

FIG. 4 is a left view thereof;

FIG. 5 is a right view thereof;

FIG. 6 is a top view thereof; and,

FIG. 7 is a bottom view thereof.

The broken lines shown on the drawings depict portions of the earmuff that form no part of the claimed design.
